(57) **CLAIM**

The ornamental design for an electrical power strip, as shown and described.

DESCRIPTION

FIG. 1 is a top plan view, illustrating an electrical power strip incorporating the design of the present invention, the phantom line portions forming no part of the design.

FIG. 2 is a front elevational view illustrating the design for the power strip of FIG. 1.

FIG. 3 is an elevational plan view illustrating the design for the power strip of FIGS. 1 and 2; and,

FIG. 4 is an enlarged right-hand end view illustrating the present invention, with the left-hand end view being a mirror image thereof.

No claim is made to the internal configuration of the electrical power strip, nor is any claim made to the bottom view, which is omitted from the drawings.
